UNITED STATES PATENT OFFICE.

ARTHUR J. TOWNSEND, OF CANTON, OHIO.

ROLLING-MILL REPEATER.

Application filed January 14, 1921. Serial No. 437,312.

To all whom it may concern:

Be it known that I, ARTHUR J. TOWNSEND, a citizen of the United States, residing at Canton, in the county of Stark and State of Ohio, have invented certain new and useful Improvements in Rolling-Mill Repeaters, of which the following is a specification.

The invention relates to a repeating mechanism for rolling mills, and the object of the improvement is to provide means for returning a strip or long sheet or thin plate of metal directly from one mill to another laterally adjacent mill without either stopping or reversing the movement of the strip.

Common practice has been to run the material entirely through one mill and then to stop and transfer the same laterally, and finally passing it by a reverse movement through a laterally adjacent mill; which several operations involve a considerable loss of time, and not only increase the cost of production, but render it difficult, if not impossible, to roll the lighter gauges.

A direct return from one mill to a laterally adjacent mill has sometimes been accomplished manually by grasping the forward end of the material with tongs, as it emerges from one mill, and carrying and entering it as quickly as possible into the laterally adjacent mill; which method of operation is not only slow and costly, but involves a great danger to the workmen engaged therein.

The present improvement involves the use of a repeater drum mounted upon an upright axis, with guide chutes leading from and to laterally adjacent mills, the one chute turning the strip from a horizontal toward a transverse upright position for passing around the drum, and the other chute returning the strip from the other side of the drum into a transverse horizontal position for properly entering the other mill.

The improvement also contemplates the use of an endless cable transmission gearing, for carrying the strip around the repeater drum, the laterally adjoining strands of the cable forming a belt continuously covering the entire width of the drum so as to carry narrow strips as well as comparatively wide strips around the same with equal facility.

A practical embodiment of the invention

is illustrated in the accompanying drawings forming part hereof in which—

Figure 1 is a side elevation of two mills and a repeater mechanism, showing one mill in section;

Fig. 2, a plan view of the same; 60

Fig. 3, an end elevation of the mills showing the repeater in rear thereof;

Fig. 4, a section of the chutes on line IV—IV, Fig. 2;

Fig. 5, a section of the chutes on line 65 V—V, Fig. 2; and

Fig. 6, a section of the chutes on line VI—VI, Fig. 2.

Similar numerals refer to similar parts throughout the drawings. 70

The repeater mechanism 1 is located in rear of the first mill 2 and in front of the laterally adjacent mill 3; and the guide chute 4 leads from the first mill to one side of the repeater, and the guide chute 5 leads from the other side of the repeater to the second mill. The repeater mechanism includes the main drum 6 mounted to operate upon an upright axis 7, and may have a smooth face 8 which may be provided with 80 peripheral flanges 9 on its side edges.

Pulley drums 10 and 10' are mounted to operate upon an upright axis at each side of the main drum 6 in front of the median line thereof, and a third pulley drum 11 85 is located in rear of the main drum 6 in the longitudinal median line thereof; all of which pulley drums are preferably grooved on their faces in the usual manner for carrying the endless cable 12, which 90 operates around the pulley drums and the rear half of the periphery of the main drum, as well shown in Fig. 2.

Two idle sheaves 13 and 13' mounted on transverse axes, and a pendent sheave 14 with 95 a weight 15 depending therefrom, may be provided in front of the pulley drum 11, around which sheaves the endless cable is passed for properly tensioning the same; and the repeater mechanism thus formed 100 may be driven by a motor 16 carried to one of the grooved drums as 10'.

It is evident that the adjacent coils of the endless cable forms a substantially continuous belt around the rear half of the face of the main drum 6 and covering the whole width thereof, and also that a strip or sheet of metal entered between the cable

belt and one side of the drum will be carried around the rear side thereof, and will be delivered in reverse direction from the opposite side thereof.

- 5 The guide chute 4 extends from the delivery side of the first mill 2, and extends to the receiving side of the repeater. The bottom of the receiving end portion of this chute is in a transverse horizontal plane to 10 receive a strip or sheet as it emerges from the rolls of the first mill, whence the bottom of the chute is spirally twisted, as well shown in Fig. 3 of the drawings, so that the outer side of the chute is raised with reference to the inner side for bringing the bottom of the chute toward a transverse upright plane at the delivery end thereof; which twisting may be accomplished, as well shown in Fig. 1 of the drawings, by inclining the outer edge of the chute upward and the inner edge slightly downward, so as to bring the delivery end adjacent to the receiving side of the repeater.

The guide chute 5 extends from the delivery side of the repeater to the receiving side of the mill 3, the rolls 17 of which are preferably located in a lower plane than the rolls 18 of the first mill. The bottom of the receiving end of this chute is located in 20 a transverse inclined plane with its lower inner side substantially in line with the lower edge of the delivery side of the repeater, with its bottom inclined upward and outward therefrom; whence the bottom of 30 the chute is twisted and inclined downward into a transverse horizontal plane at its delivery end portion adjacent to the receiving side of the roll 17 of the second mill 3.

The receiving end 19 of the chute 5 is 40 preferably flared to more certainly guide a strip or sheet into the chute, and its inner flange 20 at the same end may be extended upward and curved inward for a substantial distance to deflect the upper edge of a strip 45 or sheet outward to lie upon the bottom of the guide chute as it travels therein toward the second mill.

Anti-friction rollers 21 of the usual character may be provided in the bottoms of 50 the chutes, as shown for portions thereof in the drawings, and it is evident that when a strip or sheet of metal is delivered by the rolls of the first mill, it will travel forward in the guide chute 4, and will be gradually 55 twisted from a horizontal plane toward a transverse upright plane at the delivery end

of the chute; whence it is caught between the drum and cable-belt of the repeater, and carried in upright position around the drum to the delivery side thereof; whence it is received in the inclined end of the guide chute 5, wherein it is turned back into a transverse horizontal plane at the delivery end thereof for properly entering between the rolls 17 of the second mill.

By these means a strip or sheet is guided and conveyed from one mill operating in one direction, to an adjacent mill operating in a different direction, by being twisted from a horizontal to a transverse upright plane, and then after being turned to a different direction, is twisted back into a transverse horizontal plane for entering between the rolls of the second mill; all of which is accomplished by a continuous operation without stopping or reversing the motion of the strip, which is carried front end foremost from one to another of the two adjacent mills, operating in different directions.

Obviously the broad invention is not limited in application to adjacent mills located side by side and operating reversely in parallel directions, nor is use of a repeater mechanism employing an endless cable belt either essential to the general combination set forth or limited thereto; but the laterally adjacent arrangement of the mills is preferred for economy of space, and the cable-belt gearing is preferred in any relation 90 for more uniform and efficient action, and in the particular combination, because the coils of the cable can be inclined upward in their travel around the main drum, thus preventing any tendency for the strip or sheet to sag downward when passing in transverse upright position from one chute to the other.

I claim:

1. A rolling mill repeater including a 100 drum rotatable on an axis at an angle to a horizontal plane, and an endless belt operating around one side of the drum, for carrying a strip or the like around the drum.

2. A rolling mill repeater including a 105 drum rotatable on an axis at an angle to a horizontal plane, and an endless cable belt operating around one side of the drum, for carrying a strip or the like around the drum.

ARTHUR J. TOWNSEND.
